TUFTING IMPLEMENT

Alfred G. Garvin, Framingham, Mass.

Application December 26, 1946, Serial No. 718,531

6 Claims. (Cl. 112—80)

1

This invention relates to improvements in the art of producing hooked rugs, pertaining more particularly to the means employed in such production.

Hooked rugs as now generally produced are fashioned upon and with a fabric backing, through which a suitable yarn is passed by an implement of a particular type, the implement carrying the yarn beyond the face of the fabric sufficient to provide an extended loop formation beyond the backing, this being repeated along the lines of a pattern generally carried by the backing, each of the loops being formed separately, the yarn being carried from one loop point to the next on the opposite side of the backing. The loop formation may be left in loop form, or may be cut at its closed end, so that, in the latter case, the two loop plies become individual.

In such practice, the fabric backing is generally in the form of burlap, Hessian or any other loosely woven material—"loosely woven" as compared with the usual woven materials, such as cotton fabric, for instance. The fabric used, however, while relatively loose in weave is not formed with openings of sufficient dimensions as to permit the ready passage of the yarn loop, with the result that the implement used in producing the rug must include an element adapted to provide an opening of sufficient dimensions to receive the loop of yarn when carried by the implement through the fabric backing, the "awl" first contacting the fabric and preparing the opening through which the loop is to be passed. Since the warp and weft threads of the fabric are woven with a view to at least approximately retain their positions within the burlap fabric, the passage of the awl to produce an opening of sufficient extent necessarily affects the normal woven appearance and necessarily tends to spread the threads in the production of the opening. Hence, it can be readily understood that in following this practice, there is a tendency to disturb the normal characteristics of the fabric to an extent which causes a material weakening of the fabric itself, a condition which will necessarily decrease the life of the rug, especially since this effect is perpetuated by the fact that the opening thus produced must receive the dual plies of the loop as a permanent portion of the structure, so that the stretching action of the awl is not a temporary condition but, in a reduced form, remains as a permanent part of the rug fabric.

In other words, under prior practice, the operation is such as to tend to weaken the fabric portion of the rug, due to the fact that any inter-

2

stices effect that is present in the normal woven fabric must be inevitably varied from such normal condition by and during production of the rug with the variations maximum at the time the loops are being inserted, with the variation partially maintained by the presence of the plies of the loop so that the woven fabric no longer has the normal characteristics. And since the normal interstices are small, the practice of marking the fabric with the design to be produced is practically a necessity, since any attempt to utilize the fabric without such patterned design leaves the operation as of such "haphazard" type as to provide for a badly formed rug, due to the presence of undesired variations in the loop formation. In the practice above outlined, the burlap backing activity is practically limited to providing the base for the yarn support in the production of the rug—any pattern effect is limited to the design which is stamped thereon and which is not, of course, related to the locations of the interstices which may be present through the loose weaving that is present with burlap and the like; hence, when the awl is introduced, there is no certainty that it may not pass through the thread structure itself, thus further weakening the fabric.

In other words, the implement used in such practice practically provides all of the activities during the production of the rug. The awl must penetrate the fabric in advance of the passing of the yarn loop therethrough, in order to provide an opening of sufficient dimensions to enable the ready passage of the loop therethrough; and since the positioning of the awl disturbs the normal thread positions about the opening, and the awl remains in its inserted position during the passage of the loop through the opening and during the return of the yarn loop carrying member of the implement, after which the awl is withdrawn, the disturbed condition remains until the awl is withdrawn, after which the loop plies prevent return of the burlap threads to initial or woven positions.

As a result, the initial penetration by the awl is a matter of judgment by the operator as to location, and while the succeeding passage of the loop is within the awl itself, the rug product must therefore mainly depend for its appearance, upon the accuracy with which the operator places the successive loops and without any real physical means open to him for determining the actual spacing of successive loops. As a result, the final appearance becomes dependent upon the skill of the operator in spacing the loops, both as to aline-

ment as well as to variation from a straight line effect, thus making the product more or less haphazard as to appearance.

As with the above practice, the present invention utilizes a fabric backing and an implement for applying the yarn thereto in loop form. However, unlike such prior practice, the fabric backing cooperates with the implement in the production of a rug throughout the period of rug production, the backing ending this cooperation only when the last loop has been positioned and thereafter retains only the function of forming the loop-supporting backing of the rug. During the production period, the backing has the dual function of providing the loop support for all of the formed loops and cooperating with the implement in connection with the unlooped portion or portions of the fabric. Hence, at the start of the operation, the fabric backing is wholly cooperative with the implement, the rug backing function developing only with the completion of each loop.

This condition is brought about by the form of the fabric, the latter being especially woven for the purpose, with the weaving designed to produce a plurality of openings aligned longitudinally and laterally, in such manner that the fabric takes on the appearance of a very coarse mesh. For instance, in one form, the openings number thirty-six to the square inch—presenting six longitudinally and six laterally—the contour of the opening being approximately square; in practice, the number on each side of a square inch may range from six to eight, the result being that each opening has its side dimension slightly less than one-sixth to one-eighth of an inch in length, the weaving providing a comparatively thin division between adjacent openings.

From this it will be understood that the openings are pre-formed and definitely positioned relative to each other. As a result, the arrangement and dimensions are such that the operator readily fashions his own design, the meshed condition of the fabric being such as to practically prevent the use of a stamped design. In addition, the division wall between openings serves as a definite guide for the introduction of the loop-carrying member of the implement, thus assuring accurate positioning of the loops relative to each other. In addition to the above, it is apparent that should the loop-carrying member be of a slightly greater length than the length of a side of the opening, the comparatively large dimension opening will permit compensation for any slight stretching that may be present by temporarily reducing the corresponding lateral dimension of the opening, the temporary change from the normal pertaining simply to the wall of a single opening, and this change being present only momentarily, with the opening resuming its normal dimensions without delay, so that the product will present its loops accurately aligned longitudinally and transversely of the rug.

As is apparent, the fact that the fabric backing itself provides the space to receive the yarn loop, the implement used for the looping operation need not carry an awl formation. As a result, the implement can be greatly simplified and such is the case in the present invention, in which the assemblage is so arranged as to provide for a simple, but efficient, structure of comparatively small dimensions and capable of producing, in co-relation with the fabric backing, a hooked rug in which the applied yarns are not only positioned with uniformity and under controllable conditions, but provides such action in

a manner to produce complete uniformity in loop lengths as well as in loop positioning, so that the product, although provided by a hand operation, presents all of the characteristics that are to be expected through the use of elaborate machine operations, producing this result more rapidly than where the usual forms of hand implements are employed.

In addition, the rug produced is generally of greater wearing qualities, due to the fact that the fabric backing is not impaired in any way during the looping operation, so that although the fabric is completely hidden by the loops, it preserves all of the wearing qualities placed therein at the time of fabric formation and hence retains the serviceable qualities which the initial fabric was designed to produce. Consequently, the hooked rug formation produced is of a superior type and of maximum wearing possibilities.

To these and other ends, therefore, the nature of which will be better understood as the invention is hereinafter disclosed, said invention consists in the improved constructions and combinations of parts more particularly described hereinafter, illustrated in the accompanying drawing, and more particularly pointed out in the appended claims.

In the accompanying drawings, in which similar reference characters indicate similar parts in each of the views:

Figure 1 illustrates a plan view of a section of the fabric backing used in the invention;

Figure 2 illustrates a diagrammatic plan view showing a possible arrangement for the rug pattern;

Figure 3 illustrates a perspective detail showing loops applied to the fabric backing;

Figure 4 illustrates a plan view of the implement used in providing the loops, the parts being shown in the position occupied by the needle when the latter has been advanced to its greatest extent in forming a loop;

Figure 5 illustrates a side elevation of the implement partly in cross section and partly broken away;

Figure 6 illustrates a longitudinal section of the implement, the plane of the section being horizontal in connection with the showing of Fig. 5;

Figures 7, 8, 9 and 10 are cross sectional views taken on lines 7—7, 8—8, 9—9, and 10—10, of Fig. 6;

Figure 11 illustrates a side elevation of a bushing element for the needle end of the implement;

Figure 12 illustrates an end view of the same;

Figure 13 illustrates a longitudinal section of the same taken on line 13—13 of Fig. 11;

Figure 14 illustrates a cross section taken on line 14—14 of Fig. 11;

Figure 21 illustrates a side elevation of the yarn guide;

Figure 22 illustrates a longitudinal sectional view of the same taken on line 22—22 of Fig. 25;

Figure 23 illustrates a bottom plan view of the guide;

Figure 24 illustrates a longitudinal section taken on line 24—24 of Fig. 22;

Figure 25 illustrates an end elevation of the guide; and

Figure 26 illustrates a sectional view taken on line 26—26 of Fig. 22.

The fabric backing element of the invention is a specially prepared structure, preferably woven, being designed especially for the present service. In its production, the weft thread is heavier than the threads used for the warp, the warp threads being designed to operate in pairs with a semi-twisted condition produced during the weaving, with the pair of twisted threads practically equalling the size of the weft thread. The warp pairs of threads are spaced a distance sufficient to provide the length of a side of the square being formed, and the loom is arranged so as to advance the fabric sufficient to position succeeding weft threads the desired distance of the adjacent side of the opening. While the number of spaces per square inch may be varied, the backing is preferably so woven as to provide six spaces to the inch, making a total space count of thirty-six to the square inch. However, the number per linear inch may be increased to seven or eight, if desired, the smaller openings being used where the yarn is of a finer type. Since the weft thread and the pairs of warp threads provide a comparatively small wall texture, such threads do not materially reduce the dimensions of each opening, and due to the woven character of the fabric, the contours of such walls are generally of a square type, any variation in opening dimensions being due to the normal conditions which are present in producing meshed fabrics generally. A fabric of this type is shown at A in the drawings, with the wall threads (warp and weft) indicated at *a* and the openings at *a'*.

The implement used in providing the yarn looping operation is shown in detail in Figs. 4 to 26, and which may be considered as a "yarn looper" or as a "yarn looping needle," and is made up of a number of fabricated parts which, in the operation of the assembly in providing a loop, presents an operation such as to produce the loop efficiently, accurately and with a minimum of time required, effects produced through the cooperation of the looper with the specific type of fabric backing above described.

The looper generally comprises a tubular body 15 of circular contour and of a predetermined length, and which provides a support for the parts assembled as now described. Within the body and having a press fit therein, is a tubular guide 16 of less length than the body 15, said guide being provided with an internal rib 16a, extending lengthwise from end to end of the guide, and which may be formed in any suitable manner.

The outer end of the body carries a bushing 17, the latter being provided with a reduced extension 17a which fits within and closes the outer end of the body with the exception of an axial perforation 17b which extends through the bushing, thus closing this end of the body.

The opposite end of the body is closed by a bushing element 18 having the reduced portion 18a and axial opening 18b, this portion of the bushing being similar to that of bushing 17 and being designed to close the lower end of the body. The two bushings practically prevent longitudinal movement of the guide 16. In addition, bushing 18 carries a pair of arms 19 extending forwardly of the bushing from diametri-

cally opposite sides of the peripheral zone of the bushing, said arms being adapted to combinedly form a bracket for parts, presently referred to; these arms will be further described in connection with their relation to such other parts.

Located within guide 16 and movable longitudinally therein is a piston 20 having a working fit with the interior of the guide 16, piston 20 carrying an external longitudinal depression 20a which is designed to cooperate with the rib 16a of guide 16, the rib and depression being designed to prevent rotation of the piston on its axis while permitting longitudinal movement of the piston within the guide. The piston is provided with an axial opening 20b, the opposite end zones of which are threaded, as at 20c, these providing for connection with the piston of an operating handle connected with one end of the piston, and a looping needle which is connected with the opposite end of the piston, the arrangement being such that reciprocating movement of the handle will provide similar movement to the needle, with the extent of movement limited to the size of the lost motion relation between the piston length and the spacing distance of the inner faces of bushings 17 and 18.

The handle portion and its connecting rod, the piston 20, and the needle, provide a reciprocating plunger formation in which the stroke of reciprocation is limited by the contact of the respective and faces of piston 20 with the inner end faces of bushings 17 and 18, thus providing a definite stroke length of the piston 20 by movements of the handle, with a stroke length of similar extent for the needle.

The handle section is in the form of a rod 21 having its opposite ends threaded, one end being threaded into a threaded zone 20c of the piston with the opposite end threaded into a handle 22.

The needle, indicated generally at 23, is of suitable length with its inner end arranged for threaded engagement with the opposite threaded opening 20c of the piston. The length of the shank or stem 23a of the needle is such as to locate the looping free end thereof properly related to other parts of the assembly when piston 20 is at the extremes of its stroke. Such looping end zone, indicated at 23b extends from the end of the stem portion 23a with somewhat of a flaring appearance of its opposite sides to thereby provide the actual end of the zone as of considerably increased width—in practice, such actual end is approximately double the diameter of the stem; at the actual end, the thickness of the needle is small (approximately one-thirty-second inch), with the ends of the flared sides rounded off so as to produce an intermediate zone of such end as of less diameter than a more remote width of such end zone, such intermediate section being formed with a curved recess 23c. Such end zone may be of uniform thickness from its point of connection with the stem, or may be of a gradually increasing thickness toward such point of connection. The concave end thus produced is designed to receive and position the yarn during the looping operation. As will be understood, the width of such end is such as to approach the length of a side of one of the openings *a'*, especially where the length of a side of the opening is of the larger size; normally such end zone of the needle does not materially expand the size of opening *a'*, but is sufficiently close to the opening dimensions as to be more or less guided by opposite walls of the opening; should the opening be small, the needle end can be in-

serted on a diagonal of the opening, in which case any excess width of the needle end beyond the length of such diagonal would simply cause the opening to be temporarily changed in contour to accommodate for such excess width.

The needle operates relative to an assemblage of elements which include a presser foot, and a yarn carrier guide, the presser foot being designed to be brought into contact with the face of the fabric backing—the latter being supported in the usual manner so as to provide a more or less unyielding face, this result being generally provided by the use of a frame to which the fabric backing is temporarily secured—thus positioning the implement and its needle relative to the particular opening a' into which the loop is to be carried, the operator holding the implement firmly against the backing so as to locate the presser foot relative to the particular opening and to maintain the implement in such position during the successive needle strokes which form the cycle for producing the loop. The yarn guide is designed to bring the yarn to the proper point where the concave face of the needle can engage the yarn strand and carry it through opening a' to the desired extent.

To support these elements, bushing 18 carries the arms 19 projecting forwardly from the bushing and located at diametrically opposite points of such bushing, the arms being spaced apart a distance sufficient to permit of the location of parts between them, and being of a length sufficient to provide for efficient support for the parts. Each arm is provided on its outer face with a groove 19a extending longitudinally of the arm and symmetrical to the diameter relative to which the two arms are located, the groove extending throughout the length of the arm; each arm is also provided with an opening 19b positioned intermediate the ends of the arm and at a point closer to the bushing face than to the free end of such arm. The two grooves 19a are designed to receive the presser foot structure now to be described:

The presser foot 24 is preferably formed of wire, such as piano wire, being bent into a more or less specific shape, the latter generally presenting two spaced apart flights 24a which are joined together at one end by a semi-loop formation 24b, the loop bottom being preferably bent inward to a slight extent so that such semi-loop portion can be readily shifted relative to the fabric backing similar to the usual presser foot structures. Each flight includes a rear zone 24c spaced wider than the body of the flight, said portions 24c being adapted to be positioned in the grooves 19a, the free ends of such portions being bent inward as at 24d to form a pin structure designed to enter into and through openings 19b. As is apparent, the presser foot projected length is such that when the portion 24b is in contact with the face of the fabric backing, the remainder of the stroke of the needle will be sufficient to carry the yarn loop through opening a' and the desired distance therebeyond which represents the projected loop length, it being understood that the axis of the needle travels in a plane which approximates the plane of arms 24a of the presser foot, the stem of the needle being located in the axis of the bushing; hence, the semi-loop end 24b projects laterally of such plane and thus aids in permitting proper location of the needle end relative to the particular opening a' .

The inturned ends 24d of the presser foot

75 are adapted to be located within and extend through openings 19b, the length of such ends being sufficient to provide a support for a tension spring 25, presently described in detail, and which includes a pair of coiled portions 25a spaced from but adjacent to the free ends of the spring, the ends 24d extending into the coiled zone and thus providing a support for the spring, each end 24d carrying an individual coil. Such coils, in turn, are adapted to pivotally support pintles 26a of a yarn carrier guide 26, thus mounting the guide and spring externally of the path of travel of the needle.

Guide 26 is in the form of a U-shaped elongated element with the pintles located in the rear zone of the guide and projecting outwardly from the sides thereof, the pintless being spaced from the rear end of the guide, being located approximately on the plane of the open top of the body of the guide. When in position, the sides of the guide overlie the needle path, the guide having an inner width sufficient to permit the end 23c of the needle to pass thereinto for a desired distance. In practice, guide 26 forms a channel into which the yarn from the supply is passed and from which it emerges through the forward open end of the guide, thus providing the yarn supply for the needle activity, as presently described in detail.

Spring 25 is designed to provide a yielding support for the guide, the spring being generally U-shaped, in plan, the length of the U-shaped portion extending from the inner coils of the coiled portions 25a, the closed end zone of the U-shaped portion being preferably bent at a small angle to the sides of the U-shaped portion. Beyond the coil portion, the end zone 25b preferably engages with a part of the fixed structure in such way as to place the coil sections under a slight tension when the spring is in operative position. In practice, the U-shaped portion of the spring lies outside of the guide 26 with the closed end of the spring overlying the bottom of the guide, thus placing the guide under the tension of the spring and assuring the proper location of the guide relative to the needle travel path.

Since the guide 26 is pivotally supported in its rear end zone while the nose end of the guide underlies spring 25 and is therefore subject to the tension of the spring, it will be understood that, in the absence of the yarn, the inner face of the nose portion of the bottom of the guide will lie in contact with the needle 23, the bottom of the guide thus extending angular to the direction of length of the needle; and inasmuch as the rear end of the guide extends normal to the plane of the guide bottom, such position of the nose will also cause the rear end to extend angular to a transverse plane through the needle and to the face of bushing element 18, so that the open rear end of the guide will provide an open passage-way between the guide rear end and the bushing face through which the yarn can be introduced into the interior of the guide. By raising the nose end of the guide out of contact with the needle, the end of the yarn can be drawn lengthwise of the interior of the guide and then carried over the end of the needle. When the guide is then released, the nose will contact the inserted yarn thread with a yielding pressure, produced by spring 25. As will be apparent, the yarn so positioned relative to the guide can move through the guide with sufficient freedom to permit ready operation of the

implement, the spring pressure serving to prevent the development of any material slack conditions between the nose of the guide and the needle end due to the pressure of the spring 25 on the nose of the guide.

With the fabric backing A properly positioned relative to its supporting frame, thus placing the fabric openings a' completely visible, with with the openings of predetermined dimensions, and with a yarn strand leading from the supply into and through guide 26, the needle is moved to its housed position by drawing the handle 22 outwardly; the end zone of the yarn strand is then passed across the needle path by the operator and this portion placed over the desired opening of the fabric backing at which the initial operation is to take place, a sufficient length of strand being provided to permit formation of the loop as the handle 22 is then shifted to its opposite position, the foot of the presser being in contact with the fabric in proper position relative to the desired opening. For the initial action, the strand end zone is held by the operator, the needle advanced and passed through the opening by the continued advance of the 25 needle, the end of such stroke of the needle being provided by contact of the piston with the lower bushing 18. This provides a loop on the reverse side of the fabric with the loop of desired length, and with the strand end projecting through the opening, together with the continuation of the opposite ply of the loop, such continuation leading to the guide 26. As is apparent, if the implement is then shifted to an adjacent opening a' , the yarn continuation will be carried to the latter opening where it will be effective similar to the end zone strand above referred to. The needle may be withdrawn from the filled opening by moving the handle 22 outwardly respecting the tubular body which, of course, will leave the presser foot in contact with the fabric. If desired, the needle can be withdrawn from the filled opening by moving the implement in its entirety away from the fabric.

This cycle which involves the two opposing strokes of the needle takes place for each of the openings a' that is being included within the particular design, the operator passing from one opening to an adjacent opening, longitudinally or laterally, as the conditions may require, thus gradually developing the particular design portion which the yarn is designed to produce, it being the general practice to utilize yarns of different colors for different sections and building up the desired design by a proper selection of different yarns and providing the yarn feed with a particular yarn at the proper time.

For instance, the design may be made up of a succession of squares, the length of a side of which equals a desired number of adjacent openings a' ; each square, may in turn, be made up of a plurality of zones extending lengthwise—or crosswise, as the case may be—with each zone of several rows width and with the color scheme such that adjacent zones will be of contrasting colors. The adjacent squares may have the direction of length of their zones at right angle to the first square, so that alternate squares of the design have their direction of length, say longitudinally, while the intermediate squares will have the direction of length of their zones extending laterally. Since any color scheme may be used, a design of this type becomes very attractive, and can be readily produced in the manner above described by simply shifting the

implement from one opening to an adjacent opening a' , actuating the needle through its cycle and then shifting the implement to the next desired opening.

5 As will be understood, both sides of the rug will present the design pattern squares as similar in design and color scheme, since the design of the square is produced progressively, with each color zone practically complete in itself and 10 produced by such progressive development. While there is this similarity between the opposite sides, the side which forms the under face of the rug has its loops lying close to the warp or weft threads of the several openings, while the 15 opposite or upper side of the rug is of an extended loop formation. However, the loops of the opposite sides are distinguished through the fact that the plies of a loop of greater length are located entirely within an opening a' , while the 20 plies forming the loop of the under face of the rug are located in different openings a' , with the loop itself overlying a warp or weft thread, as the case may be. This is due to the fact that the under loop is formed by the shifting of the implement from one opening to the next, the loop being formed from one ply of the opening which has received the longer loop and, in turn, provides a ply of the loop to be formed, by shifting the implement to such adjacent opening, thus 25 crossing the warp or weft thread which separates the two openings.

While the openings of the fabric backing are pre-formed and of practically fixed dimensions, both before and after the looping operation, with the plies of the loops practically filling one dimension of the opening, the arrangement may not produce the tightening effect that is set up where the fabric is of burlap and in which there may be a tendency of the threads to grip the plies; this difference is not material in service, due to the fact that the under loops lie in close contact with the floor or under surface and hence are not liable to be withdrawn through the opening, it being obvious that the longer loop is so formed that although exposed on the floor, any pressure placed thereon would not act to cause movement of the plies through the opening; as a result, the rug becomes practically equal in serviceability to rugs formed with a burlap backing, so far as integrity of the loops is concerned; the fact that, however, there is no impairment of warp or weft threads during production of the rug such as is more or less inherent with the burlap backing, renders a rug of the present invention of greater serviceability than the burlap rug, due to the greater life of the rug, thus providing a definite advantage. Obviously, the fact that the loops are based upon the uniform openings of the fabric and therefore of greater regularity in arrangement, the design of the hooked rug may be made more elaborate with assurance of a successful result, and the completed rug will 50 present a far superior appearance. However, while the rug of the present invention may have its loops less tightly held by the warp and weft threads, although this does not materially affect the serviceability, as above explained, the present development offers the additional advantage of the greater simplicity in production of the rug loops, and hence, greatly reducing the length of 55 time required to produce the rug, these being of positive advantage during the rug production and producing a rug of superior appearance value.

ferred embodiment of the present invention, it will be understood that changes and/or modifications therein may be found desirable or essential in meeting the various exigencies of service or the individual desires of the user; I therefore reserve the right to make any and all such changes or modifications therein as may be found desirable or essential, insofar as the same may fall within the spirit and scope of the invention, as expressed in the accompanying claims, when broadly construed.

I claim:

1. In the production of hooked rugs, a loop-inserting implement comprising a tubular body carrying a reciprocating needle and its actuating means axially aligned with the body axis, a yarn guide pivotally supported by the body and projecting therefrom in the direction of loop-development movement of the needle, means on said yarn guide defining a partial housing for the needle when the needle is in retracted position, spring means operatively connected with the tubular body and bearing against the yarn guide to normally urge the yarn guide about its pivot whereupon the free end of the yarn guide contacts the needle and a presser-foot formation supported by the body with the presser-foot projecting normal to the needle travel path beyond the free end of the yarn guide, said needle having its forward end concaved to definitely locate the yarn thread relative to the needle during advance of the latter, said implement being cooperative with a fabric backing having preformed openings of predetermined dimensions arranged in succession longitudinally and transversely of the fabric for locating the loop position and controlling the loop insertion through the opening by the advance of the needle during its loop-forming stroke.

2. An implement as in claim 1 characterized in that a piston reciprocates within the body in a fixed path of predetermined length controlled by the body, the needle being carried by and movable with the piston, the length of a piston stroke being such as to move the free end of the needle between positions on opposite sides of the presser foot.

3. An implement as in claim 1 characterized in that the yarn guide is U-shaped in cross section and open-ended for the free introduction of the yarn through one end zone and discharge through the opposite end zone, said guide being symmetrically positioned relative to the needle axis to permit the needle to have its movements within and lengthwise of the guide.

4. An implement as in claim 1 characterized in that the yarn guide is U-shaped in cross section and open-ended for the free introduction of the yarn through one end zone and discharge through the opposite end zone, said guide being symmetrically positioned relative to the needle axis to permit the needle to have its movements within and lengthwise of the guide, said guide having its inner end zone provided with outwardly projecting pins constituting a pivotal mounting for the guide relative to the axis of the implement.

5. An implement as in claim 1 characterized in that the yarn guide is U-shaped in cross section and open-ended for the free introduction of the yarn through one end zone and discharge through the opposite end zone, said guide being symmetrically positioned relative to the needle axis to permit the needle to have its movements within and lengthwise of the guide, said guide having the rear end zone of its side walls enlarged in the plane of such walls, with the outer face of each of such walls carrying an outwardly projecting pin having the pin axis intersecting the axis of the implement and its needle with the pins constitute a pivot for the guide to permit swinging action of the guide relative to the needle path.

6. An implement as in claim 1 characterized in that the presser foot is formed of wire, bent to provide a generally U-shaped formation in the direction of length of the presser foot, with the opposite sides fixedly carried by the body of the implement to locate such sides approximately parallel to the needle, with the opposite end of the U-shaped formation bent laterally in the direction of the guide to constitute means for engagement with the work.
